UNITED STATES PATENT OFFICE.

WILLIAM C. GRUNOW, OF CHICAGO, AND OWEN E. GRIGSBY, OF PARK RIDGE, ILLINOIS,
ASSIGNORS TO GRIGSBY-GRUNOW-HINDS CO., OF CHICAGO, ILLINOIS, A CORPOR-
ATION OF ILLINOIS.

ELECTRIC CIGAR LIGHTER.

Application filed June 21, 1924. Serial No. 721,530.

Our invention relates to electric cigar lighters, being directed more particularly to devices of the above character adapted for use on automobiles or other places where 5 a spring retracted cord and heating element may be employed.

There are various objects to our invention, one of them being the provision of an improved device of the above character which 10 is compact, simple of construction, positive in operation and which may be readily applied in various ways, such as to the dash through an opening therein, or to the steering column.

15 There are various features and advantages in construction and operation of our improved device, which will be more particularly pointed out in the ensuing part of the specification and appended claims.

20 For a better understanding of our invention reference is to be had to the accompanying drawings, in which—

Fig. 1 is a side elevation of the preferred form of our invention as mounted on the

25 dash;

Fig. 2 is a vertical longitudinal section through a portion of the device, but with one of the side disks of the casing removed and showing the outside of the reel spool;

30 Fig. 3 is a view similar to a portion of Fig. 2, showing the other side of the reel spool with the wiping contact which is controlled by the heating element to open the circuit when the heating element is retracted;

35 Fig. 4 is an enlarged sectional view of the heating element;

Fig. 5 is a rear view of Fig. 4;

Fig. 6 is a front view of Fig. 4 in section through the ring 44 and ferrule 40 with the 40 washers 42—43 removed;

Fig. 6^a is a front view of Fig. 4;

Fig. 7 is a sectional view along the line 7—7 of Fig. 2;

Fig. 8 shows the device attached to the 45 steering column; and

Fig. 9 is a perspective view of the clamp used for applying the device to the steering column.

Referring now more in detail to the form 50 of our invention as shown herein, it comprises a suitable reel spool preferably spring retracted and including side flanges 10—11 suitably ribbed to strengthen them and insulatingly mounted on a spool hub in the

form of a metallic sleeve or tube 12. The 55 insulating mounting is preferably accomplished by using a fibre sheet 13 in the form of a sleeve inserted between the spool flanges 10—11 and the sleeve 12, as indicated in Fig. 7. The flanges 10—11 are pressed on over the 60 insulating sleeve 13, so as to be rigidly and tightly held on the tube 12.

The entire spool, including its sleeve hub 12, is rotatable in the casing and to this 65 end the casing is made up of opposite but like disk portions 14—15 formed up of sheet metal and having central bearings 14' and 15', pressed inwardly to support the ends of the sleeve 12 and on which this sleeve is 70 freely rotatable. The disk 14 is preferably integral with the ring 20 but the disk 15 is a removable or separate cap. A separator tube 16 is provided to assist in holding the casing sides apart and rigid, so that the spool 75 sleeve may readily rotate on its bearings. To fasten the casing sides we preferably use a rod 17 extending through the separator tube and having nuts 18 threaded thereon so as to clamp the elements 14—15 against the 80 ends of the separator tube. Thus a very firm and rigid structure is provided, but at the same time permitting a ready rotation of the spool.

The spool being preferably spring retracted, we provide a very effective construction for this purpose by inserting a retracting spring 19 between the separator tube 16 and spool hub 12, one end of this spring being secured by passing through an opening in the casing disk 14, and the other end of the 85 spring being secured to the spool by extending through the sleeve 12 thereof.

The casing which includes a peripheral element in the form of the said tubular portion 20 has an opening cut therein from points 21 90 to 22, as indicated in Fig. 2, to permit the cord and heating element extension to pass through. Over this opening is secured an angular box-like section 23, formed up of sheet metal and attached to the peripheral 95 casing member 20 by rivets 24. This section 23 has a tube 25 secured thereto, said tube being shouldered at 25' and then turned over on its inner end 25^a so as to securely fasten the tube to the casing. The clamping nuts 100 26—27 are threaded onto this sleeve 25, the outer nut 27 being in the form of a ferrule member to give a finished appearance to the

outside of the device and also provide a smooth rounded surface over which the cord is drawn.

Referring again to the reel spool, a conductor cord 28 is shown wound thereon, being preferably a two-strand conductor, the inner ends of which extend through the spool flanges and are suitably electrically connected therewith, preferably by soldering, as indicated in Figs. 2 and 7.

In order to provide an electrical connection with this conductor 28 we apply wipers or contacts for engagement with the side of the spool flanges. These contacts are flat 15 spring bronze members, one of which also acts as a switch to open and close the circuit of the lighting element as it is pulled from the reel and restored. This latter contact member 29 shown in Figs. 3 and 7 is preferably of such a shape as will give it greater 20 length and resiliency, being insulatingly fastened at one end to the casing tube 20, as indicated in Fig. 7, and carrying a binding post 29³ to which the incoming current conductor 25 is attached. This contact 29 has a projecting portion 29' adapted to contact with the flange 10 of the spool when the heating element is drawn out, but which portion 29' is disengaged from the flange when the heating element 30 is seated as indicated in Fig. 7. This operation of the contact is brought about by the insulated extension 29², which is engaged by the rounded end of the heating element extension as it restores to its seat, as indicated 35 in Fig. 7. When the heating element is drawn out it disengages from the tip 29² and allows the contact portion 29' to engage the spool and thus closes the circuit. The other strand of the reel conductor which is shown connected to 40 the spool flange 11 and has a contact 30 resting against its side as indicated in Figs. 2 and 7, so as to be in wiping contact therewith. This contact 30 is also insulatingly attached to the casing tube 20 and carries a binding post 30³ grounded to the frame and to which the other incoming conductor is attached.

We find that if desired, contact wiper 30 may be dispensed with as with binding post 30³ grounded to the frame, it is only necessary 50 to connect the corresponding conductor of 28 directly to tube 12 and thus the circuit extends through the frame of the device on one side.

Now as to the lighting element and holder therefor, the holder is preferably in the form of a metallic tube 31 drawn together at its inner end 31 so as to provide a cam surface for operating the contact spring 29 and also permit a more ready entry of the holder 31 into the socket or tube 25. This tube 31 carries a block 32, preferably of insulating material as fibre, so that the block may be forced into the tube 31 with one of the terminals of the conductor 28 between the wall of sleeve 31 and the block 32, thereby providing an in-

timate contact between sleeve 31 and the conductor so as to extend the electrical connection to the lighting unit, as will be described. The insulating block 32 also carries a metallic sleeve 34 adapted to receive a binding screw 70 35 by which the other strand of the conductor 28 is fastened, so as to extend the circuit through to the heating unit, as will be described. In order to more firmly hold the block 32 in position the sleeve 31 has several 75 indentations 31² made therein, as indicated in Figs. 2 and 7.

Now as to the lighting element, which is more clearly shown in the enlarged views Figs. 4, 5 and 6, we provide a suitable base 36 of insulating material, preferably porcelain, having an undulating face 36' on which the resistance element 37, preferably in the form of a suitable wire, is placed. This wire 37 is extended back and forth so as to provide a suitable surface for lighting a cigar or cigarette, one end of the wire extending down through the recess 36² of the block beneath the head of the central terminal screw 38. This screw passes through the block 36 and is secured by a nut 39, the end of the screw 38 being adapted to thread into the sleeve 34 to attach the heating unit to the holder sleeve 31. The other end of the resistance wire 37 passes through a slot 36³ in the periphery of the porcelain block 36 and is clamped between the metallic sleeve 40 and contact plate 41, which is in electrical engagement with the sleeve 31. The metallic sleeve 40 serves to hold the parts of the lighting unit together, the outer curled edge resting against a metallic washer 42 with an insulating washer 43, preferably of mica, positioned between the washer 42 and resistance wire 37, thereby insulating the wire 37 from the metal sleeve 40. The rear contact plate 41 is sheared so as to provide yielding contact fingers 41', which engage the edge of the holder tube 31 as the element is threaded on so as to effect a more intimate contact between these parts 31—41. An insulating cover for the heat element is provided, also acting as a heat shielding handle 44, by which it may be grasped when it is to be pulled from the socket for use. This outer or protective covering 44 is assembled with the inner elements by shellacing the inner face thereof and forcing the sleeve 40 therein. Of course, the base 36 and heating wire 37 with the washers on opposite sides of base 36 are assembled in the sleeve 40 before it is placed in the protective covering 44, by putting these elements into the sleeve 40 and spinning the inner end over the contact washer 41 to hold the parts firmly together.

Thus a simple but effective heating unit is provided, which may be readily removed for repair or replacement by unscrewing it from the holder.

The circuit from the rear conductor 28 to 130

the resistance wire 37 extends from one strand of the conductor to the shield or sleeve 31 of the holder, through this shield 31 to washer 41, over wire 36 to the central terminal post 38, sleeve 34 to the other or lower strand of conductor 28.

It will be apparent from the above that when the incoming or feed wires are attached to the binding posts of contacts 29-30, the 10 circuit extends through these wiper contacts to the metal flanges of the reel spool, then through the reel conductor 28 to the lighting unit. Normally this circuit is open by reason of contact point 29 being disengaged from 15 the flange 10 of the spool, but as soon as the heating unit is pulled from its socket the cam portion 31' of the lighter sleeve leaves the extension 29², allowing contact point 29' to engage the spool flange 10 to close the circuit. 20 The resistance unit then, of course, becomes lighted and upon restoring the element to its socket the circuit is again interrupted when the sleeve portion 31' engages the extension 29² and lifts contact point 29' from electrical 25 engagement with the spool flange.

What we claim as new and desire to secure by United States Letters Patent is:

1. A device of the character described comprising a spring retracted reel spool with 30 cord wound thereon and having a conductor ring, a contact in wiping engagement with the ring and circuit with the cord, a lighting element connected with the cord and retracted by the winding of the cord on the spool, and means engaged by the element when retracted for disengaging the wiping contact and ring to open the circuit of the element.

2. A device of the character described comprising a spring retracted reel spool with 40 cord wound thereon, said spool including metallic side flanges insulatingly mounted on the hub and acting as conductor rings and to which one end of said cord is connected, a pair of contacts each one of which is in wiping engagement with the outside face of one

of the flanges, a lighting element connected with the other end of the cord and retracted by the winding of the cord on the spool, and means engaged by the element when retracted for interrupting the connection between one 50 of said wiping contacts and spool face to open the circuit of the element.

3. In a cigar lighter of the character described, a lighting unit comprising a circular flat base-block of suitable insulating material, a resistance element distributed over the front face thereof having one terminal connected to a central binding post extending from the rear face of the block and the other terminal extending through the block over 55 the rear face of the block, a metallic terminal plate positioned against the rear face of the block in contact with said other terminal of the element, and a metallic tubular enclosure over the outside of the block curled over the front face to hold the element in place and over the rear to hold the rear terminal plate.

4. In a cigar lighter of the character described, a lighting unit comprising a circular flat base-block of suitable insulating material, 70 a resistance element distributed over the front face thereof having one terminal connected to a central binding post extending from the rear face of the block and the other terminal extending through the block over 75 the rear face of the block, a metallic terminal plate positioned against the rear face of the block in contact with said other terminal of the element, a metallic tubular enclosure over the outside of the block curled over the front face to hold the element in place and over the rear to hold the rear terminal plate, 80 and a heat-proof insulating sleeve surrounding the metallic enclosure into which the latter is pressed and whereby the unit may be 85 grasped when used.

In witness whereof, we hereunto subscribe our names this 28 day of May, 1924.

WILLIAM C. GRUNOW.

OWEN E. GRIGSBY.
